UNITED STATES PATENT OFFICE

173,126

HOLY WATER BOTTLE

Alfred F. Reilly, Sr., Taunton, Mass., assignor to Evans Case Co., North Attleboro, Mass.

Application November 12, 1953, Serial No. 27,562

Term of patent 14 years

(Cl. D58—8)

To all whom it may concern:

Be it known that I, Alfred F. Reilly, Sr., a citizen of the United States, residing in Taunton, in the county of Bristol and State of Massachusetts, have invented a new, original, and ornamental Design for a Holy Water Bottle, of which the following is a specification, reference being had to the accompanying drawing, forming part thereof.

Figure 2 is a side elevation thereof, both sides being substantially the same in appearance; and,

Figure 3 is a front or rear elevation thereof, both front and rear being substantially the same in appearance.

The lines in the narrow circular bands on the drawing are for shading purposes.

I claim:

The ornamental design for a holy water bottle, as shown and described.
